UNITED STATES PATENT OFFICE.

CLEMENS GRAAFF, OF BERLIN, GERMANY, ASSIGNOR, BY MESNE ASSIGNMENTS, TO
THE CHEMICAL FOUNDATION, INC., A CORPORATION OF DELAWARE.

CARTRIDGE FOR CHEMICAL FIRE-EXTINGUISHERS.

1,338,828.

Specification of Letters Patent.

Patented May 4, 1920.

Application filed May 26, 1915, Serial No. 30,861. Renewed September 24, 1918. Serial No. 255,529.

To all whom it may concern:

Be it known that I, CLEMENS GRAAFF, a subject of the German Emperor, and residing at 17 Linkstrasse, Berlin, W. 9, Germany, have invented certain new and useful 5 Improvements in Cartridges for Chemical Fire-Extinguishers, of which the following is a specification.

The present invention relates to a cartridge for chemical fire-extinguishers, which 10 does not entail any danger of an explosion in consequence of a drop or a blow, and with which, when in use, the reaction of the chemicals contained in it proceeds so calmly, 15 that it is impossible for the said chemicals or the products of the reaction to be driven out of the container of the extinguisher, and that gas is generated during the whole period of operation of the extinguisher, so 20 that the jet of liquid emerging from the latter will have a constant reach. The fact that with the cartridge according to the present invention only gases emerge from it during its operation, renders the said cartridge 25 suitable for use not only in fire extinguishers employing a liquid of any composition, but also with the so-called dry extinguishers.

The cartridge is adapted to be positioned 30 within a suitable fire extinguisher casing and contains a chemical or a mixture of chemicals adapted to produce the gas, in a chamber which is subdivided by a plurality of perforated partitions. Another chemical 35 or mixture of chemicals is contained in a capsule, which is displaceably disposed in the cartridge and is adapted to be opened in a suitable manner, when the extinguisher is operated. This capsule is connected with 40 the lid of the cartridge in such a manner, that when the cartridge falls into a position which admits of reaction between the several constituents, it will tear a hole in said lid, through which the gases generated may 45 escape, so that the cartridge can not burst due to an excessive internal pressure.

In the accompanying drawing a preferred embodiment of the present invention is exemplified.

50 In this drawing *m* is a cylindrical container or vessel, which is closed at one end by a bottom wall *1*, and close to its other end by a lid *u*. The latter has an opening *2*, which is sealed by a lead foil *3* or the like. Within the cartridge is disposed a

capsule *q*, which contains one of the chemicals or a mixture of chemicals for generating the gas, and these chemicals may, if necessary, be incased in a glass vessel *t*. The vessel *t* is supported in a suitable manner, within the capsule *q*, with the object of avoiding its being broken, if the cartridge should fall or receive a blow, not intended to operate the cartridge. The capsule *q* is, furthermore as hereinbefore stated, displaceable within the cartridge. It is centered in the vessel *m* by means of scalloped flange disks or teeth *4*. A pin *5* connected to the capsule *q* passes with a close joint through the said lead foil *3* and is secured 60 in a metal disk *6* the diameter of which is smaller than that of the opening *2* in the lid *u* of the cartridge, so that the latter may be opened by means of a percussion pin, a movable plunger or the like *P*, fitted to the 65 extinguisher and entering into the cartridge for displacing the capsule *q*. If the cartridge when in position in a fire extinguisher casing should fall to the ground in about the position shown in the drawing, 70 the capsule *q* will, according to the force of the impact, either be held unmoved, so that it will not be opened, or, it will by its kinetic energy break the lead foil *3* by means of the pin *5* and the disk *6*. Thereby an opening 75 is produced in the cartridge, through which, in case the capsule is unintentionally opened, the gases may escape into the fire extinguisher casing which is adapted to inclose it without causing any danger. 80

The capsule *q* is provided with a neck *s*, which is sealed at its upper end by means of a lead foil *7* or the like. Into this neck engages a tube *9* secured to the bottom *1* of the cartridge and having holes *8* at its lower 85 end. The neck *s* of the capsule *q* slides in a perforated tube *10*, which serves to distribute the chemicals emerging from the capsule, and also for limiting the stroke of said capsule. 90

In the lower part of the vessel *m* are disposed a number of perforated cylinders *11*, concentrical around the tube *10*, so that a number of chambers is produced, which communicate with each other and which are 105 connected at the top by a perforated plate *12*.

The operation of the cartridge is as follows:

By means of the percussion pin secured to 110

the fire extinguisher, or a movable plunger or the like, P a blow is exerted against the disk 6, whereby the lead foil 3 is broken. The plunger thereupon pushes the capsule 5 *q* forward until the tube 9 breaks through the lead foil 7 at the upper end of the neck of said capsule, penetrates into the interior of the capsule and there breaks the vessel *t* containing the chemicals. The further displacement of the capsule *q* is then prevented by the edge of tube 10, so that the perforated plate 12 will not be covered and closed by the bottom of the capsule *q*.
 The chemical emerging from the capsule 15 *q* enters into the tube 10 and emerges from the same through the numerous perforations thereof gradually into the adjoining chamber, and thence into the other chambers mixing with the chemicals contained in 20 these chambers. By such means the reaction of the chemicals acting upon each other in the cartridge for generating the gas proceeds quite calmly, uniformly and so slowly, that on the one hand, no mixing 25 chemicals will be ejected until they have become extinguishing chemicals, and on the other a constant pressure is produced in the fire extinguisher, whereby the reach of the latter will remain constant from the beginning to the end of its operation.

The gas produced by the reaction passes through the annular space formed between the wall of the capsule *q* and the wall of the vessel *m* and through the opening 2 into 35 the container of the fire extinguisher not shown in the drawing. The chemicals flowing downward and the gases rising upward, thus, travel along entirely different paths, whereby the calm operation of the cartridge is furthermore considerably improved.

Chemicals likewise enter from the capsule *q* into the tube 9, containing other chemicals and penetrating into the capsule *q* in 45 operating the cartridge. Thus there will be a chemical reaction in this tube as well. The gas there produced enters into the capsule *q* and facilitates the discharge of the chemicals therefrom.

50 I claim:

1. A cartridge for chemical fire extinguishers having a reaction chamber, means dividing the reaction chamber of said cartridge into a plurality of smaller chambers, 55 cells or the like.

2. A cartridge for chemical fire extinguishers having a reaction chamber, the reaction chamber subdivided by perforated partitions into a plurality of small chambers, cells or the like.

60 3. A cartridge for chemical fire extinguishers having a reaction chamber, means

dividing the reaction chamber of said cartridge into a plurality of smaller chambers, a chemical in said chambers, a displaceable capsule, containing another chemical positioned within said cartridge and in close proximity to said reaction chamber and adapted to react on said chemical in the reaction chamber and thereby generate gas, 65 means for limiting the stroke of said capsule, said capsule provided with a neck, adapted to enter the reaction chamber on the displacement of said capsule.

4. A cartridge for chemical fire extinguishers having a reaction chamber, means dividing the reaction chamber of said cartridge into a plurality of smaller chambers, a chemical in said chambers, a displaceable capsule, containing another chemical positioned within said cartridge and in close proximity to said reaction chamber and adapted to react on said chemical in the reaction chamber and thereby generate gas, 70 means for limiting the stroke of said capsule, said capsule provided with a neck, adapted to enter the reaction chamber on the displacement of said capsule, a tube attached to said reaction chamber adapted to penetrate into the capsule on the displacement of the latter, said tube containing the first chemical and adapted to receive a part 75 of the chemical contained in the capsule.

5. A cartridge for chemical fire extinguishers having a reaction chamber, means dividing the reaction chamber of said cartridge into a plurality of smaller chambers, a chemical in said chambers, a displaceable capsule, containing another chemical positioned within said cartridge and in close proximity to said reaction chamber and adapted to react on said chemical in the reaction chamber and thereby generate gas, 80 means for limiting the stroke of said capsule, said capsule provided with a neck, adapted to enter the reaction chamber on the displacement of said capsule, a tube attached to said reaction chamber adapted to penetrate into the capsule on the displacement of the latter, said tube containing the first chemical and adapted to receive a part 85 of the chemical contained in the capsule.

5. A cartridge for chemical fire extinguishers having a reaction chamber, means 90 dividing the reaction chamber of said cartridge into a plurality of smaller chambers, a chemical in said chambers, a displaceable capsule, containing another chemical positioned within said cartridge and in close proximity to said reaction chamber and adapted to react on said chemical in the reaction chamber and thereby generate gas, 95 means for limiting the stroke of said capsule, said capsule provided with a neck, adapted to enter the reaction chamber on the displacement of said capsule, a tube attached to said reaction chamber, adapted to penetrate into the capsule on the displacement of the latter, said tube containing the first chemical and adapted to receive a part 100 of the chemical contained in the capsule, said capsule attached to the lid of the cartridge, a readily broken seal in said lid, the said capsule adapted to break said seal, in 105 case the cartridge should drop or receive a blow.

In testimony whereof I affix my signature in presence of two witnesses.

CLEMENS GRAAFF.
